E. TYDEN

DRY PIPE VALVE ACCELERATING DEVICE

Filed August 25, 1923

UNITED STATES PATENT OFFICE.

EMIL TYDEN, OF EVANSTON, ILLINOIS.

DRY-PIPE-VALVE-ACCELERATING DEVICE.

Application filed August 25, 1923. Serial No. 659,331.

The purpose of this invention is to provide an improved construction in a dry pipe sprinkler system for accelerating the opening of the dry pipe main valve upon the opening of the sprinkler head with a specific purpose of preventing the opening of the main valve upon an occurrence of minor negligible leakage in the air system amounting to less than would occur through a single open sprinkler head. It consists in the elements and features of construction shown and described as indicated in the claims.

In the drawings:—

Figure 1 is a partly sectional front elevation of a dry pipe valve casing and connected water and air pipes equipped with the devices embodying this invention, the dry pipe valve casing being partly broken away and shown in section through the inter-

20 seat chamber below the main valve.

Figure 2 is a side elevation from the side at which the hand hole of the main dry pipe valve casing is located.

Figure 3 is a detail section at the line, 3—3, on Figure 5 showing the parts on an enlarged scale.

Figure 4 is a section at the line 4—4, on Figure 2.

Figure 5 is a section at the line, 5—5, on Figure 6.

Figure 6 is an elevation looking in the direction of the arrows, 6—6, on Figure 2.

Figure 7 is a plan view of a detail seen looking in the direction of the arrow, 7, on Figure 1.

In the structure shown in the drawing, A is the dry pipe valve casing, B the water in lead pipe, C the pipe leading to the sprinkler system which, in the normal condition of the apparatus, when set for its purpose, is occupied by air in compression. D is the dry pipe main valve having the usual construction for seating at two concentric seats, A¹⁰ and A¹¹, between which there is the usual interseat chamber, a, in which the pressure is normally atmospheric, so that the compressed air pressure, operating above the valve B, over the larger area defined by the outer seat A¹¹, as compared with the area defined by the inner seat A¹⁰, over which the water pressure is operative, insures the valve D being held seated by a super-atmospheric pressure in the system of about 30 lbs. against water pressure in the main which may reach 100 lbs. When a sprinkler head

is opened, causing reduction of the super-atmospheric pressure in the system which eventually results in the dry pipe main valve D being opened by the water pressure and the water thereby being sent to the open sprinkler head, it is desirable that the opening of the valve should be delayed as little as possible after the sprinkler head is opened and the reduction of air pressure in the system begins; but when only a single sprinkler head is opened by the fire, it may require a very appreciable length of time for the air pressure to be reduced so as to permit the dry pipe main valve to open. The purpose of the present invention is to cause the amount of reduction of air pressure in the system which will be experienced almost instantly upon the opening of a single sprinkler head, to result in overcoming the differential pressure upon the upper side of the

60 valve which holds it seated, so that the valve will open almost instantly upon the opening of the sprinkler head. This is effected by means of devices which are sensitive to the slight reduction of pressure which occurs almost instantly upon the opening of the sprinkler head, and which, responding to that slight reduction, operate to open a communication from C, one of the pressure regions,—the region of water pressure operating over the lesser area of the valve D, or the region of air pressure operating over the greater area of the valve,—to the inter-

70 seat chamber, a, below the dry pipe main valve, hereinafter referred to as the “atmospheric pressure chamber.”

These devices are designed with the view to responding, as indicated, to the reduction of pressure which follows the opening of a single sprinkler head, while not responding to less reduction of pressure which may result from minor negligible leakages in the system. These devices will now be described.

80

Bracketed upon any convenient part of the structure, as for example, upon the air pipe C, as shown, there is a plate G upon the upper side of which there are applied two flexible diaphragms, g and g¹ which are suitably secured at their margins by spider clamps, G² and G³, the plate G has under each diaphragm an aperture, said apertures being of different diameters, the aperture g², under the diaphragm retained by the spider G², being larger than the aperture, g³, under the diaphragm retained by the spider

110

G². From the air pipe C of the system, a pipe H leads by branches H¹ and H², to the plate G, being connected thereto at the apertures g² and g³ respectively. To the diaphragms g and g¹, there are applied stems, J and J¹, which obtain guidance at the center of the spiders G² and G³ respectively, and springs L and L¹ coiled around said stems, react against the under side of the guide 10 bearings of the stems in the spiders for flexing the diaphragms toward the plate G, as seen in dotted line with respect to one of them in Figure 4.

K is a lever pivotally connected with both 15 the diaphragm stems, its connection to the stem, J¹, being slotted for accommodating the movement of the lever rocking about its pivot to the other stem, J. From the water main, B, a pipe, P, leads to the interseat or 20 atmospheric pressure chamber, a, by way of a valve, M, which is interposed in said pipe. The valve, M, is of the turn cock type, and at the protruding larger end of the valve member there is mounted for rocking freely, 25 a weighted lever, comprising the sleeve or hub, N, which is journaled upon the turn cock body, and has a weighted lever arm, N¹. At what may be regarded as the normal position of the turn cock valve, being the position 30 at which the pipe P is closed, the lever arm, N¹, stands in the position shown in Figure 2 with the weight, N², at the left hand side of the vertical plane of the axis of the lever where it is held by a latch, T, 35 engaging a stud, n, which projects from the weight, N², said latch being the shorter arm of a bell crank lever fulcrumed on the dry pipe valve casing and having its longer arm, T¹, extending upward from the fulcrum. 40 From the lever, K, an arm, K¹, extends down to a point a short distance lower than the upper end of the arm, T¹, and is there deflected horizontally, forming a terminal finger, K², which projects across the arm, T¹, 45 in contact therewith at the weight-latching position of the latch lever.

The operation of the structure above described is that when a reduction of pressure occurs in the system, due to the opening 50 of a sprinkler head, the aperture, g³, under the diaphragm, g¹, being less than the aperture, g², under the diaphragm, g, the change of pressure is transmitted more slowly to the diaphragm, g¹, than to the diaphragm, g, 55 and in consequence, the stem, J¹, following the collapse of the diaphragm, g¹, carries down the right hand end of the lever, K, causing the lever to pivot about its connection with the stem, J, and causing the arm, K¹, carried rigidly with the lever, and swinging, therefore, about the same pivot, 60 to swing in against the lever arm, T¹, of the latch and disengage the latch from the weight, whereupon the weight falls through an arc of approximately 135 degrees, the

pin, m¹, after about 30 degrees of that fall, encountering an abutment, m², which projects from the valve member of the turn cock, so that the weight in its further fall, turns the turn cock valve member through 70 90 degrees, that is from closed to open position, admitting water pressure from the pipe, P, into the chamber, a, where, operating over the entire area of the valve, D, it causes the valve to be instantly opened 75 against the air pressure above it in the system.

It will be understood that when change in pressure in the system occurs slowly, as from minor and negligible leaks, such slow change is experienced so nearly simultaneously, or an equal rate under both the diaphragms, that if they collapse at all, their collapse will be substantially equal, and the movement of the lever, K, will be a bodily movement downward, causing it at all positions to be parallel with its original position, that is, without pivotal action over either of its pivots; and in such movement, it will be observed that the end K² of the lever arm, K¹, will move along that lever arm, T¹, without any tendency to displace the latch from its normal weight-engaging position.

When the dry pipe valve is to be reset, the attendant will also reset the accelerating device, by closing the turn cock valve by means of the weighted lever arm, N¹, before the water is admitted from the water main to the dry pipe valve casing. In this operation, the stud, n, on the weight, N², becomes engaged with the latch, T, and the lever arm, K¹, is restored to vertical position and restores the lever, K, to its normal horizontal position where it will be held by the compressed air, reaching the diaphragms from the system when the air pressure is admitted to the system in the usual way.

It will be obvious that the same diaphragm mechanism and connections operated thereby may admit pressure from the region of air pressure to the interseat chamber as easily and as effectively as from the region of water pressure. The construction shown in the drawings is such as to permit the operator to choose between utilizing the air pressure or the water pressure for the purpose of the device. For admitting the air pressure a pipe, P⁵, connected with the air pipe, C, above the dry pipe valve casing, extends down and is connected at one end of the stem of the T, P⁶, in the pipe line, P, which leads from the water pipe, B. In this line, P⁷, there is interposed a shut-off valve, P⁷, and in the pipe, P, between the water pipe, B, and the T, P⁶, there is also interposed a shut-off valve, P⁸. When it is desired to utilize the air pressure for the purpose of the device, the operator will close the valve, P⁸, and open the valve, P⁷. When 110 115 120 125 130 135

the water pressure is to be utilized the valve, P^7 , will be closed and the valve, P^8 , will be opened.

In order that the desired pressure may be developed in the interseat or atmospheric pressure chamber, a , by the establishment of communication between said chamber and either of the fluid pressure regions of the system, it is necessary that the valve, D' , 10 which controls the drainage port from said interseat chamber shall be closed when the pressure communication mentioned is established. For this purpose the drainage valve, D' , is fulcrumed at one side of its seat and 15 has a lever arm, d' , in the form of a vane or plate which at open position of the valve extends obliquely upward across the line of discharge of the pressure jet so as to be tilted over for closing the valve by the impact of 20 said jet. This lever arm is suitably weighted to hold the valve, D' , normally open when it has once been set at open position, as shown in Figure 1, and in the range of movement from open to closed position of 25 the valve the lever arm passes to substantially upright position so that the valve, once closed, is held closed by gravity.

I claim:—

1. In a dry pipe sprinkler system, in combination with a dry pipe main valve constructed for exposing different areas to the water and air pressures respectively at its opposite sides, having for that purpose at the water inlet side a chamber in which the pressure is normally substantially atmospheric; a passage leading from the region of one of said pressures to said atmospheric pressure chamber; a valve adapted to be closed controlling said passage; an expandible and reducible chamber device consisting of two chambers exposed to air pressure from the system reaching different areas of the chamber wall through ports affording unequal access to the two chambers respectively, where- 45 by change or air pressure in the system causes temporarily unequal pressures upon the moving walls of said two chambers; operating connections from the expandible and reducible chamber device for transmitting the resulting wall movement to the pressure- 50 passage-controlling valve, for opening the same upon predetermined difference of pressures on the moving walls of said respective chambers, said connections comprising pivoted means connecting the two movable chamber walls, and adapted to move at the points of connection respectively according to the differential movements of the two chamber walls; and operating connections 55 from said pivoted means for transmitting its angular movement resulting from said differential movements of the chamber walls to the second mentioned valve.

2. In a dry pipe sprinkler system, in combination with a dry pipe main valve con-

structed for exposing different areas to the water and air pressures respectively at its opposite sides, having for that purpose at the water inlet side a chamber in which the pressure is normally substantially atmospheric; a passage leading from the region of one of said pressures to said chamber; a valve adapted to be closed controlling said passage; an expandible and reducible chamber device comprising two chambers exposed to air pressure from the system reaching the movable walls of the respective chambers through ports affording unequal access to the respective chambers; thrust members actuated by the chamber walls respectively; a lever pivotally connected to both the thrust members, one of said pivotal connections being adapted to communicate the movement of the lever about its pivot to the other thrust member; a second lever, parallel with the first mentioned lever with which the first mentioned lever moves when carried by equal thrusts of the two thrust members and transversely of which said first member moves when rocking about its pivotal connection with either of the thrust members, said two levers being engaged for rocking of the second lever about its fulcrum by said rocking movement of the first lever, and connections by which the said rocking movement of the second lever causes the operation of the normally closed valve.

3. In a dry pipe sprinkler system, in combination with a dry pipe main valve constructed for exposing different areas to the water and air pressures respectively at its opposite sides, having for that purpose at the water inlet side a chamber in which the pressure is normally substantially atmospheric; a passage leading from the region of one of said pressures to said chamber; a valve adapted to be closed controlling said passage; an expandible and reducible chamber device exposed to air pressure from the system reaching different areas of the chamber wall through ports affording unequal access thereto; operating connections from the expandible and reducible chamber device for transmitting the resulting wall movement to the pressure passage controlling valve for opening the same upon predetermined difference of pressures on different moving wall areas of the expandible and reducible chamber device, the second mentioned valve being of the turn-cock type, the means for turning its moving element consisting of a part mounted rotatably on said element, and co-operating cam features on said rotating part for relatively displacing said elements longitudinally in a limited initial part of the relative rotative movement of the co-operating parts thereon, for slackening the frictional engagement of the turn-cock parts before giving the opening move- 115

120 125 130

4. In the construction defined in claim 3, a weighted lever mounted on the turn-cock for rotation thereabout; releasable means for holding it, the cam elements being on said weighted lever and valve stem respectively, and co-operating for camming the valve stem longitudinally in the initial part of the falling movement of the lever.

5. In a dry pipe sprinkler system, in combination with a dry pipe main valve constructed for exposing differential areas to the water and air pressures respectively, at its opposite sides, and having for that purpose at the water inlet side a chamber in which the pressure is normally substantially atmospheric; a passage leading from the region of one of said pressures to said chamber; a valve controlling said passage and means for operating said valve to admit the pressure to said atmospheric pressure chamber, said chamber having a drainage port and a valve controlling the same which is adapted to be set and remain normally at open position in the set up of the dry pipe valve, and means connected with said last mentioned valve exposed to the pressure admitted through said passage and adapted to be actuated thereby for closing the drainage

valve when the pressure communication is established.

6. In the construction defined in claim 5, foregoing, the drainage valve being fulcrumed at one side of its seat and adapted to be held seated by gravity, and lever means connected therewith for holding it open by gravity when it has been set at open position, said lever means extending across the path of the pressure admitted through said passage for actuation thereby in direction for seating said drainage valve.

7. In the construction defined in claim 5, foregoing, the drainage valve being fulcrumed at one side of its seat and having a lever arm extended at such angle to the valve and of such weight as to hold the valve seated by gravity when it has been set at closed position and to hold it open by gravity when it has been set at open position, said lever arm at the open position of the valve extending in the path of the pressure admitted through said passages for actuation thereby to seat the valve.

In testimony whereof, I have hereunto set my hand at Chicago, Illinois, this 16th day of August, 1923.

EMIL TYDEN.
